INVENTOR:
GEORGE HATTOY.

Soultz & Soultz,
ATTORNEYS

UNITED STATES PATENT OFFICE.

GEORGE HATTOY, OF WOONSOCKET, RHODE ISLAND, ASSIGNEE TO CROMPTON & KNOWLES LOOM WORKS, OF WORCESTER, MASSACHUSETTS, A CORPORATION OF MASSACHUSETTS.

COMBINED THREAD CUTTER AND CLAMP.

Application filed August 14, 1924. Serial No. 731,960.

This invention relates to a combined thread clamp and cutter for weft replenishing looms and an object of the invention is to provide a device of this character wherein the cutting motion is derived from the lay but under control of the transerrer mechanism, the cutter operating by the joint action of the lay and transerrer.

In weft replenishing looms it is desirable to cut the thread of the outgoing bobbin at the time of transfer and to clamp the same to prevent it from being drawn into the cloth. Under normal conditions the cutter is preferably out of the range of the shuttle so that should the latter be improperly boxed it will not strike the cutter on the forward beat of the lay. In the type of replenishing mechanism shown in Patent No. 1,030,748 the transerrer latch is lifted into engaging position with the bunter on the lay when the indicating shuttle approaches the replenishing mechanism but should the shuttle be improperly boxed the replenishing mechanism is revoked to prevent transfer and under such conditions it is desirable to prevent operation of the cutter.

Accordingly, it is a more particular object of my invention to provide a cutter and clamp normally out of the path of the shuttle and moved to open position by the replenishing mechanism but depending for movement to cutting position upon the transerrer mechanism so that should the replenishing mechanism be revoked after the cutter jaws are opened the cutter will not move rearwardly to sever the thread.

It is a further object of my invention to provide an angularly movable cutter blade which will serve also as one of the clamping elements, this construction requiring that the cutter be normally closed and opened only prior to transfer.

With these and other objects in view which will appear as the description proceeds, my invention resides in the combination and arrangement of parts hereinafter described and set forth in the claims.

In the accompanying drawings, wherein one form of my invention is shown,

Fig. 1 is a side elevation of a weft replenishing mechanism having my invention applied thereto as viewed from the central portion of the loom;

Fig. 2 is a front elevation of the parts shown in Fig. 1, and

Fig. 3 is a top plan view of the parts shown in Fig. 2.

I have shown my invention as applied to a multi-color weft replenishing mechanism having a frame 10 in the upper portion of which is mounted for angular motion a shaft 11 the forward end of which is provided with a lever 12. An arm 13 extends from the lever and is connected with the upper arm 14 of a lever 15 which is pivoted at 16 on the frame 10. Depending from lever 15 is a connector 17 the lower end of which is bent upwardly to form a loop 18 which surrounds the transerrer latch 19. The latter is pivotally mounted between arms 20 depending from the hub 21 of the transerrer arm 22 which is pivotally mounted on fixed stud 23. At the time of transfer the shaft 11 is given a clockwise rotation as viewed in Fig. 2 which results in raising connector 17 so that latch 19 will be lifted into the path of the bunter 24 on the lay 25. The matter thus far described is of the usual construction and forms no part of my present invention.

In carrying out my improvements I provide the lever 12 with a connector 30 the lower end of which is connected to an arm 31 secured to rod 32, said rod extending between bearings 33 on the breast beam 34 and being bent rearwardly and having a curved end as at 35.

Secured to the breast beam is a frame 36 which is slotted to receive a slide 37, said slot being closed at the upper portion thereof by a plate 38 which prevents displacement of the slide 37. The rear end of the slide 37 is formed as a cutter 39 and has pivoted thereto an angularly movable cutter blade 40 which moves pivotally about the bolt 41 carried by the slide. Said blade 40 has depending therefrom a foot 42 positioned to engage the lay when the cutter is in operative position. A flexible clamping plate 43 is secured to the slide and engages that part of the cutter 40 opposite the cutter 39. A pin 44 carried by cutter 40 limits the closing movement of the cutter.

The forward portion of the slide 37 has upstanding therefrom a pin 45 which passes through a slot 46 formed in the end of lever 47. The lever 47 is pivoted on an upright

fixed stud 48 and has threaded therein a push rod 49 the forward end of which is threaded to receive lock nuts 50 and the rearward end of which is offset as at 51 to 5 provide a shoe for engagement with one of the arms 20. A coil spring 52 surrounds the stud 48 and has the lower end thereof secured in fixed position and has its upper end in engagement with lever 47, said spring 10 normally holding the lever in the position shown in Fig. 3 with the shoe 51 in contact with one of the arms 20. The shoe is angularly adjustable on the lever to vary the point at which the lever and shoe contact 15 with each other.

Under normal conditions the parts are in the position shown in full lines in Figs. 1 and 3 with the cutter and clamp closed and in forward position so as to be out of the 20 path of a misplaced shuttle. The parts will remain in this position until a transfer is about to take place, at which time the latch 19 and connector 30 will be raised, the former to set the transerrer latch 25 and the latter to move the bent end 35 of the rod to the dotted line position shown in Fig. 1. As end 35 swings on its pivot it will engage foot 42 and move member 40 about the pivot thereof. The cutter 30 will remain in this open but inoperative position until the bunter 24 engages the latch 19, at which time the transerrer arm will be lowered and the arms 20 moved forwardly. As said arms move toward the front the 35 shoe 51 will rock lever 47 about its axis against the action of spring 52 and the slide 37 will be moved rearwardly, the motion being derived from the transerrer mechanism and timed so as to move rearwardly as the 40 lay moves forwardly. As the lay approaches front center it will engage the foot 42 to cause the pivoted cutter to co-act with cutter 39 to sever the thread, the latter being clamped between flexible blade 43 and cutter 40 to prevent the same from being 45 drawn into the shed.

It will be seen that the relative motion of the cutter with respect to the lay is approximately double the motion of the lay itself so that the time for starting the cutter 50 on its rearward movement can be delayed to give the shuttle more time to enter the box. In moving the cutter rearwardly at a rate which is approximately proportional 55 to the forward advance of the lay I am enabled to cut the filling at a faster rate than would be possible if the motion were derived from the lay alone and I find this to be an advantage in certain classes of 60 yarn where a quick motion of the cutter is more likely to sever the thread than a slower movement. Also, although the cutter is moved to open position by the replenishing mechanism it is not moved to operative position except on a transferring beat, revoca-

tion of the replenishing mechanism being effective to prevent movement of the cutter to cutting position.

Having thus described my invention it will be apparent that changes and modifications may be made therein by those skilled in the art without departing from the spirit and scope of the invention, and I do not wish to be limited to the details herein disclosed, but what I claim is:

1. In a weft replenishing loom, transerrer mechanism, a lay, thread cutting mechanism, and means having a portion to be engaged and moved forwardly by the transerrer mechanism on a transferring beat of 80 the lay, said means having another portion to move rearwardly and move the cutting mechanism toward the lay.

2. In a weft replenishing loom, a transerrer, a lay to actuate the same, a thread cutter normally in forward inoperative position, and connections between the cutter and the transerrer to move the cutter toward the lay to operative position as the transerrer is actuated by the lay, the cutter being controlled in all of its movements toward the lay by the transerrer mechanism.

3. In a weft replenishing loom, a lay, a thread cutter normally in inoperative position, and means to derive motion from the lay and impart said motion to the cutter to move the same bodily to operative position toward the lay as the latter advances, said cutter being under positive control of the means and lay during the movement of said 100 cutter toward the lay.

4. In a weft replenishing loom, a lay, a transerrer mechanism operable by the lay, a thread cutter and clamp combined normally in closed inoperative position, means to open the cutter and clamp by the replenishing mechanism, means to move the cutter and clamp bodily to operative position by the transferring mechanism when the latter is operated by the lay, and means operable by 105 the lay to close said cutter and clamp as the latter advances, said cutter and clamp being under positive control of the lay on the movement of said cutter and clamp toward the lay.

5. In a weft replenishing loom, a lay, a transerrer mechanism operable by the lay, a cutter slideable toward and from the lay and normally in inoperative closed position, a lever operatively connected to said thread 120 cutter and actuatable by the transerrer mechanism when the latter is operated by the lay to move said slide positively throughout movement thereof toward the lay.

6. In a weft replenishing loom, a lay, a 125 transerrer mechanism operable by the lay, a thread cutter slideable toward and from the lay and normally in forward closed position, a lever operatively connected to the thread cutter, an angularly adjustable pusher 130

carried by the lever and normally in engagement with a portion of the transferrer mechanism, and resilient means to position said lever to hold the thread cutter in forward position, said pusher being moved forwardly by the transferrer mechanism when the latter is operated by the lay to oscillate the lever and move said cutter rearwardly.

7. In a weft replenishing mechanism, a transferrer mechanism operable thereby, a combined thread cutter and clamp normally in closed inoperative position, means to open the cutter and clamp by the replenishing mechanism, means to move the cutter and

clamp toward the lay to operative position 15 by the transferrer mechanism as the latter is operated by the lay, means to close the cutter and clamp by the lay, and means to move the cutter and clamp forward to inoperative position as the lay recedes from 20 its forward position, said cutter and clamp being controlled as to position by the trans- 25 ferrer mechanism in all positions occupied thereby when moving toward and from operative position.

In testimony whereof I have hereunto affixed my signature.

GEORGE HATTOY.
